UNITED STATES PATENT OFFICE.

FREDERICK S. GLINES, OF LYNN, MASSACHUSETTS, ASSIGNOR TO LORENZ MUTHER,
OF NEWTON, MASSACHUSETTS.

FOLDING MACHINE.

Application filed October 28, 1922. Serial No. 597,507.

This invention relates to folding machines, and more particularly to the type of folding machine shown in an application filed by me jointly with Lorenz Muther in the 5 United States Patent Office on July 24, 1922, Serial No. 576,965.

The main object of the invention is the provision in a folding machine of a pressing member which is adjustable in a line 10 substantially transverse to the normal line of feed of the machine.

Another object of the invention is the provision of a fold turner or plow which is resilient and yielding in order to permit 15 bulky portions of the work to pass underneath the folding or turning surface without strain.

Other objects of the invention will be more specifically set forth and described 20 hereinafter.

In the drawings illustrating my invention, Figure 1 is a rear side elevation of the operative end of a folding machine of the type shown in said application hereinbefore referred to; Fig. 2 is an end elevation of the same; Fig. 3 is a horizontal sectional view of the pressing means on line 3—3 in Fig. 1; and Fig. 4 is a view in perspective of a turner or plow embodying my invention.

In the drawings, 15 indicates a lower arm and 16 an upper arm of the machine, 19 a lift shaft, 20 a feed-bar and 21 a co-operating idler roll. The feed-bar 20 is mounted in a housing 22 which is secured to a feed-shaft not shown whereby a forward and backward movement is imparted to the feed-foot 24 formed on the lower end of the feed-bar when the feed-shaft is rocked. The feed-bar is moved up and down 40 in the housing 22 through the rocking of the lift-shaft 19 by means of an arm 25 fixed on the end of said lift-shaft and suitable connections with a split collar 28 secured to the upper end of the feed-bar 20 which is held in a lowermost position by a spring 30. The idler roll is loosely mounted 45 on a screw stud 32 set in the end of the lower arm.

By the foregoing means the feed-foot is 50 given a four-motion feed. In its forward movement, it is in a lowermost position, co-operating with the idler roll to feed the material. At the end of the feeding movement, the rocking of the lift-shaft 19 through the medium of the arm 25 and con-

nections lifts the feed-bar to release the material, and the feed-bar remains in an elevated position during its backward motion, at the end of which it is dropped into its initial position. The material is thereby fed 60 in a step-by-step manner.

For guiding the material to be bound a guide bar 35 having its lower end formed with a guiding edge is slidably mounted in bearings 37 and 38 on a bracket 39 secured to the upper arm in such position that the guide-bar is held in a depending position over the work, the guiding edge being adapted to engage the edge of the material above the tape or binding material. A split block 70 40 is adjustably mounted on the guide-bar 35 and secured thereto, and a helical spring 43 mounted on the guide-bar 35 and abutting the upper bearing 37 and the split block 40 tends to hold the guide-bar in a downward position, with the split block 40 in engagement with the lower bearing 38. The split block 40 may be provided with a handle 44 for raising the guide-bar 35 out of operative position, and the bracket 39 may 80 be provided with a recess 46 adapted to receive the end 47 of the split block, so that by turning the block into said recess the guide-bar is held out of operative position. It may be restored to engagement with the 85 material by throwing the split block 40 out of the recess and allowing the spring 43 to force the guide-bar downwardly. This arrangement permits the guide-bar to be placed in an inoperative position at any 90 time and for so long a time as may be desired. The guide bar may be adjusted vertically by releasing the block 40, changing its position on the guide-bar and refastening it in adjusted position.

A work-support 50 having a bevelled edge 51 toward the operator is mounted upon the end of the lower arm 15, and upon the side toward the operator is arranged stationary means for wiping over or straightening out 100 the tape in a direction away from the material as the work is fed through the machine. The wiper is in the form of a thin plate 53, having a portion 54 bent under the bevelled portion 51 of the work plate, and is provided with a turned-up, slightly hooked-over, thin edge 55; this edge being oblique to the normal line of feed. The edge runs from left to right and is adapted to be engaged by the tape; the sharp edge 110

55 gripping the tape and drawing it from left to right, that is, away from the material to which it is stitched as the work is fed through the machine which straightens 5 out the tape into flat condition and prepares it for the turning operations.

For turning the tape upwardly and tightly around the edge of the material, a plow or turner 58 is provided, located in position to engage and turn up, by its turning 10 face 59, the tape as it leaves the wiper 53.

For pressing down the turned-over tape upon the reverse side of the material to be bound, I provide a presser-arm 60 carrying 15 a presser 62. The presser arm 60 is fixedly mounted on a lever 65, secured thereto by a screw 66, and held against rotation thereon by a pin 67. The presser arm may be made integral with the lever 65, if desired. This 20 lever is provided with a shaft 68, loosely mounted in a bearing 70 formed on the upper arm, and is arranged to oscillate therein.

Secured in the perpendicular portion of the lever 65 is a threaded screw 72 adapted 25 to be held in adjusted position by a check nut 73 and bearing at its end 75 against a block 76, set in an arm 77, fixedly mounted on the end of the lift-shaft 19. Through the medium of these parts, the lever 65 is rocked 30 by the oscillation of the lift-shaft 19 to raise and lower the presser arm and presser member, and the machine is so timed that the presser member is down between the feeding movements and elevated during the feeding 35 movements. To hold the lever 65 in the position shown in Fig. 1 with the spring 75 abutting the block 76, a spring 80 set in a hollow screw 81 bears against the upper portion of the lever 65. The screw is threaded 40 through an arm 83 forming a part of the upper arm 16 of the machine, and the pressure exerted upon the lever 65 by the spring 80 may be adjusted by turning the screw 81 one way or the other.

45 All of the foregoing construction is fully shown and described in said joint application hereinbefore referred to, to which reference may be had for a more complete description of said construction and of its functions and mode of operation.

The novel features of my invention reside, first, in the means provided for supporting the plow in a yielding position, and secondly, in making the presser 62 adjustable in a 55 direction substantially transverse to the normal line of feed. The first of these novel features consists in mounting the plow 58 upon a resilient plate 91 provided with a slot 92 whereby it may be secured adjustably 60 to the work-support 50 by a headed screw 93. The plow may be either attached to the plate 91 or made integral therewith. Preferably the work support is provided with a recess adapted to receive the plate 91 so that its 65 top surface is flush with the top surface of

the work-support. In consequence of this construction, the plow may yield upwardly to a slight extent to permit thickened portions of the work such as seams and the like to pass underneath the nose 94 of the plow 70 without straining or dragging the material. This is a distinct advantage because the distance between the under side of the nose of the plow and the work-support is so short that thickened portions of the material are 75 apt to catch and stretch the material frequently causing the pressed down binding to be pulled away from the reverse side of the material. This difficulty is entirely obviated by providing a resilient support for the 80 plow.

The second feature of my invention consists in making the shaft 68 upon which is mounted the presser-arm 60 and lever 65 adjustable longitudinally in the bearing 70 85 so that the presser 62 may be adjusted in a direction transverse to the normal line of feed. A helical spring 95 is mounted on the shaft 68 between the bearing 70 and the lever 67 and on the other end of said shaft 90 is mounted a nut 96 by means of which the shaft 68 may be moved longitudinally in one direction or the other and locked in said adjusted position by a set nut 97. Upon the end of the shaft is mounted a short arm 98 95 provided with a hole 99 to which may be attached a chain connected to a foot-treadle so that the presser arm 60 may be raised whenever desired.

By making the presser arm 60 and presser 100 62 adjustable, the machine may be adapted to folding binding of various widths. The presser 62 is recessed on its pressing surface between the foot 63 and the main body of the presser which recess permits the folded 105 over binding on convex curves of small radii to form naturally into pleats and the main body of the presser completes the pressing of these pleats. In folding wide binding if the presser is too close to the plow there is 110 a tendency for the binding to be crowded and creased between the plow and the recessed portion of the presser which prevents the binding being folded smoothly upon the reverse side of the material. This difficulty 115 is entirely obviated by moving the presser arm and presser further away from the plow to suit the width of the binding through the adjustment described.

120 Although I have shown my invention as applied to one type of folding machine, it is not to be restricted to that particular type since it is susceptible of application to folding machines generally.

What I claim is:—

1. In a folding machine, the combination of means for feeding material having a binding attached to one edge thereof, means for turning said binding in a reverse direction around the edge of said material, said means

- being normally stationary but being capable of yielding in an upward direction to permit seams and thickened portions of the work to pass thereunder and means for pressing 5 said binding upon the reverse side of said material.
2. In a folding machine, the combination of means for feeding material having a binding tape attached to one edge thereof, a 10 plow for turning said tape around the edge of said material, said plow being capable of yielding in an upward direction to permit thickened portions of the work to pass thereunder without straining, and means for 15 pressing said turned-over tape down upon the reverse side of said turned-over material.
3. In a folding machine, the combination of means for feeding material having a binding tape attached to one edge thereof, a plow 20 for turning said tape around the edge of said material, said plow being mounted upon a resilient plate to permit yielding in an upward direction, and means for pressing 25 said turned-over tape down upon the reverse side of said material.
4. In a folding machine, a combination of means for feeding material having a binding tape attached to one edge thereof, means 30 for turning said tape around the edge of said material and means for pressing said turned-over tape down upon the body of said material; said pressing means being pivotally mounted on a shaft which is longitudinally 35 adjustable.
5. In a folding machine, the combination of means for feeding material having a binding tape attached to one edge thereof, means 40 for turning said tape around the edge of said material, a loosely mounted shaft, a pressing member fixed on said shaft and means for locking said shaft in any longitudinally adjusted position.
6. In a folding machine, the combination 45 of means for feeding material having a binding tape attached to one edge thereof, means for turning said tape around the edge of said material and pivotally mounted means for pressing said turned-over tape down upon 50 the reverse side of said material; said pressing means being adjustable on its pivot axis in a direction longitudinally of its pivotal axis and transverse to the normal line of feed.
- 55 7. In a folding machine, the combination
- of feeding means, and fold-turning means normally stationary but resiliently mounted to permit it to yield in an upward direction to permit thickened portions of the work to pass thereunder without straining and 60 fold pressing means.
8. In a folding machine, the combination of feeding means, fold-turning means, and pivotally mounted fold pressing means; said fold pressing means being adjustable 65 longitudinally of its pivoted axis and transverse to the normal line of feed.
9. In a folding machine, the combination of feeding means, fold-turning means normally stationary but resiliently mounted to 70 yield in an upward direction to permit thicker portions of the work to pass thereunder, said fold-turning means being adjustable in a direction transverse to the normal line of feed, and fold-pressing means. 75
10. In a folding machine, the combination of feeding means, a plow normally stationary but resiliently mounted to permit it to yield in an upward direction when required to allow thicker portions of the work to pass 80 thereunder, said plow being adjustable in a direction transverse to the normal line of feed, and fold-pressing means.
11. In a folding machine, the combination of means for feeding material having a binding tape attached to one edge thereof, a plow 85 for turning said tape around the edge of said material, said plow being normally stationary but resiliently mounted to permit yielding in an upward direction when thicker 90 portions of the work pass thereunder, and being adjustable longitudinally and in a direction transverse to the normal line of feed, and means for pressing said turned-over 95 tape down upon the reverse side of said material.
12. In a folding machine, the combination of means for feeding material to be folded, an elongated plate having its longitudinal axis perpendicular to the normal line of 100 feed and being adjustably mounted at that end removed from said feeding means, said plate being resilient to permit its free end to be moved upwardly under pressure, fold-turning means mounted on the free end of 105 said plate and fold-pressing means.

In witness whereof, I hereunto set my hand this 20th day of October, 1922.

FREDERICK S. GLINES.
